(57) **CLAIM**

The ornamental design for a seven passenger pedaled vehicle, as shown and described.

DESCRIPTION

FIG. 1 is a front perspective view of a seven passenger pedaled vehicle showing my new design, with the pedals, cranks, tires, seats, seat posts, and brake lever being drawn in ghost and not being part of my design, and with the front wheels being turned slightly to the right in this view.

FIG. 2 is a right side perspective thereof, the left side being a mirror image.

FIG. 3 is a top perspective thereof; and,

FIG. 4 is a rear perspective thereof.

The under side does not form any part of the claimed design.
